UNITED STATES PATENT OFFICE.

G HARRY CASE, OF PHILADELPHIA, PENNSYLVANIA.

PUNCHING AND SHEARING MACHINE FRAME.

1,279,255.

Specification of Letters Patent. Patented Sept. 17, 1918.

Application filed April 18, 1917. Serial No. 162,836.

To all whom it may concern:

Be it known that I, G HARRY CASE, a citizen of the United States, and a resident of Philadelphia, in the county of Philadelphia and State of Pennsylvania, have invented 5 certain new and useful Improvements in Punching and Shearing Machine Frames; and I do hereby declare that the following is a full, clear, and exact description there- 10 of, reference being had to the accompanying drawings, and to the characters of reference marked thereon, which form a part of this specification.

This invention relates to improvements in 15 frames for punching machines, shearing machines, forming machines and the like, and the invention consists in the combination and arrangement of the parts shown in the drawings and described in the specification, 20 and is pointed out in the appended claims.

Heretofore it has been the practice to make this type of machine frame either from an integral metal casting or from flat rolled plates riveted and doweled to an intermediate 25 filler member. A disadvantage of the use of metal castings is found in the excessive weight of such castings required in order to obtain the required strength, and is found also in the liability of blow holes 30 in castings and of other foundry defects.

A disadvantage of the type of frame which is made up of flat plates which are riveted and doweled to an intermediate filler member is found in the cost of fabrication of 35 such frames, and also in the liability of the rivets and dowels to shear, or to become loose in the apertures of the parts through which they pass, so that the frame tends to rack under heavy stresses and strains.

40 In accordance with the present invention it is the purpose to produce the frame from two rolled flanged steel plates, each plate constituting preferably one half of the entire frame, and said rolled flanged plates 45 are joined at their corresponding edges through the medium of an oxyacetylene or arc welding process in such manner that when the welding operation is finished the frame consists in effect of an integral hollow sheet metal frame. Castings of suitable 50 shape may be applied to and between the members of the frame before or after they are welded and rigidly joined to the frame members to provide means for supporting 55 the frame, and also means to support shaft journals and other bearings for the opera-

tive mechanism of the punch press, or other machine.

The box section thus given to the frame imparts great lateral and vertical stiffness 60 to the frame when used for punching, shearing, forming and like machines, while at the same time the frame is light and inexpensive, as compared to a cast metal frame or multiple sheet metal frame of the same 65 strength.

The shaping of the two halves of the frame may be effected by either an ordinary type of sectional flanging press or by larger blanking presses, which latter may 70 be made to form a complete frame member at one movement, with suitable dies.

I have shown in the drawing a frame embodying the invention and will describe the same with reference to such illustrated form. 75 It will be understood, however, that the said invention is capable of some variations within the spirit and scope of the claims hereto appended.

As shown in said drawings:— 80

Figure 1 is a side elevation of a frame embodying my invention, stripped of the operative mechanism of the machine.

Fig. 2 is a vertical section on line 2—2 of Fig. 1. 85

Fig. 3 is a section taken through one of the arms of the frame.

Fig. 4 is a like section of an alternative construction.

Fig. 5 is a detail of the welded joint. 90

The frame 10 shown in Fig. 1 is a typical frame for a punching machine. It comprises in general terms a deep, rear main portion 11, a base portion 12, and an upper overhanging portion 13, forming between 95 the base portion and overhanging portion a deep throat 14. The frame as herein shown is made of two like sheet metal rolled or swaged plates 15, 15 which are provided at their outer edges with flanges 16, and are 100 provided at their inner edges, around the throat 14, with flanges 17. If it be desired to strengthen the frame at the throat the metal may be swaged or rolled outwardly beyond the planes of the plates 15 to constitute deep hollow stiffening ribs 18, as shown in Figs. 1, 2 and 3. As shown in Fig. 4, such strengthening ribs are omitted.

After the plates have been thus formed they are assembled with the edges of their 110 flanges 16 and 17 together in the position indicated in Figs. 2, 3 and 4, and are held

pressed together by any suitable pressure mechanism while subjected to a welding operation. The flanges 16 and 17 are shown as beveled at their edges so as to produce, 5 when the flanges are thus mated for welding, V-shaped grooves in which are placed strips of welding or bonding material 19. After the welding heat is applied and the plates are joined, the welded joints may, if desired, be chipped and finished so that the frame, in addition to being structurally an 10 integral or one piece device, has all the appearance of a one piece frame.

The flanges of the frame may be notched 15 to receive castings, such as the base supporting casting 20 and the bearing supporting casting 21, so that said castings become parts of the frame, being rigidly attached thereto by rivets or other suitable means. At the 20 front of the frame, the frame members may be so shaped as to leave openings to receive the arms 22, 23 and upper and lower end castings 24, 25, respectively, and said end castings may be attached to the sheet metal frame through the medium of rivets 26, 27. The shape of said end castings will depend 25 upon the kind of machine in which the frame is embodied and need not be further described. The said front casting 25 constitutes, in addition to means for supporting a die or anvil, also a base support 28 which 30 co-operates with the base support 20 to support the machine frame.

I claim as my invention:—

35 1. A hollow sheet metal frame comprising a rear vertical portion and upper and lower, forwardly extending portions, forming

ing between the same a throat, said frame comprising two sheet metal plates having exterior mating flanges and interior mating 40 flanges about the throat, with said flanges welded together to produce an integral, box-like frame.

2. A hollow sheet metal frame comprising a rear vertical portion and upper and lower, 45 forwardly extending portions, forming between the same a throat, said frame comprising two sheet metal plates having exterior mating flanges and interior mating flanges about the throat, with said flanges 50 welded together to produce an integral, box-like frame, and tool supporting and die supporting castings fixed to the ends of said upper and lower members.

3. A hollow sheet metal frame comprising a rear vertical portion and upper and lower, forwardly extending portions, forming between the same a throat, said frame comprising two sheet metal plates having exterior mating flanges and interior mating 55 flanges about the throat, with said flanges welded together to produce an integral, box-like frame, and castings applied to said plates at their junctions and attached thereto 60 for the purpose set forth.

In witness whereof I claim the foregoing as my invention; I hereunto append my signature in the presence of two witnesses at Philadelphia, Pennsylvania, this 22nd day of March, 1917.

G HARRY CASE.
